Constance R. Denoy and Helen Brenner Cuny,
Cliffside Park, N. J.

Application March 9, 1948, Serial No. 145,006

Term of patent 7 years

(Cl. D34—11)

To all whom it may concern:

Be it known that we, Constance R. Denoy and Helen Brenner Cuny, both citizens of the United States, both residing at Cliffside Park, in the county of Bergen and State of New Jersey, have invented a new, original, and ornamental Design for a Savings Bank, of which the following is a specification, reference being had to the accompanying drawing, forming a part thereof.

In the drawing:

Fig. 1 is a front elevational view of a savings bank showing our new design;

Fig. 2 is a rear elevational view; and

Fig. 3 is a side elevational view of the same.

We claim:

The ornamental design for a savings bank, as shown.

CONSTANCE R. DENOY.
HELEN BRENNER CUNY.
